UNITED STATES PATENT OFFICE.

CHARLES E. WIRTH, OF WATERBURY, CONNECTICUT, ASSIGNOR TO PLUME AND ATWOOD MANUFACTURING COMPANY, OF WATERBURY, CONNECTICUT, A CORPORATION OF CONNECTICUT.

WICK-RAISER.

SPECIFICATION forming part of Letters Patent No. 733,106, dated July 7, 1903.

Application filed February 6, 1903. Serial No. 142,138. (No model.)

To all whom it may concern:

Be it known that I, CHARLES E. WIRTH, a citizen of the United States, residing at Waterbury, in the county of New Haven and State 5 of Connecticut, have invented an Improvement in Wick-Raisers, of which the following is a specification.

My invention relates to a wick-raiser especially adapted for Argand lamps, the same 10 having an adjustable function—that is, the possibility of arresting the upward movement of the wick at the desired or a predetermined position, according to the height of the flame desired, also adjusting the parts employed as 15 the wick burns, so as to keep the wick at the proper height for a smokeless flame.

In carrying out my invention and in combination with a rack-and-pinion structure for raising and lowering the wick I employ a device 20 capable of arresting the movement of the rack-and-pinion device, especially with the upward movement of the wick, and which device is adjustable for regulating the extent of this upward movement.

25 My invention is represented by several forms, the details of which are hereinafter more particularly described.

In the drawings, Figure 1 is a vertical section, and Fig. 2 a sectional plan at xx of Fig. 30 1, of a burner embodying a form of my invention. Fig. 3 is a partial vertical section rearward of the section Fig. 1, showing the stop device. Fig. 4 is a vertical section, and Fig. 5 a vertical section and partial elevation, of a 35 burner and associated parts embodying a further form of my invention. Fig. 6 is a sectional plan at yy of Fig. 5. Fig. 7 is a vertical section, and Fig. 8 a vertical section at right angles to the section Fig. 7, representing 40 part of a font and still another form of my invention.

In Figs. 1 to 3, inclusive, a represents the wick-tube; b , the air-distributer; c , the central draft-tube, and g the wick. The wick-raiser 45 comprises the perforated tube d , having occasional inturned prongs at the respective ends; the pinion e , meshing with a line of perforations of the tube d ; the tubular stem e' , and the knurled disk e^2 on the end of said tubular stem, there being brackets 2, receiving the

tubular stem e' and secured to the wick-tube a and coming at opposite sides of the pinion e . Within the tubular stem e' and extending from end to end thereof is a shaft f , on the inner end of which is secured a tooth f' , while 55 on the outer end of the said shaft f is a nut f^2 . The tooth f' in the position Fig. 3 is adapted to contact with the surface of the tube a , and when the shaft f is given a half-revolution said tooth comes into the dotted 60 position beneath and is again adapted to contact with or stop against the wick-tube a . This movement indicates and controls the extent of the rise and fall of the wick. The parts are so constructed that the shaft f is obliged to 65 turn with the tubular stem e' because the nut f^2 on the screw-threaded end of said shaft bears against the end of the tubular stem, while the tooth f' bears against the other end of said tubular stem. Consequently when the 70 nut is clamped in position the tubular stem and the shaft turn together.

To adjust the wick, the nut is loosened and the tubular stem e' turned to elevate the wick to a position where the flame may burn 75 without smoking. The nut is then tightened to clamp the parts to said tubular stem. If now the tubular stem is turned to lower the wick, it will be found that the movement is sufficient in a half-revolution to lower the 80 wick below the wick-tube to a position where the flame is sure to be extinguished.

Referring to the structure Figs. 4 to 6, inclusive, a' represents the wick-tube; b' , the air-distributer; c' , the central draft-tube, which 85 extends to the bottom of the oil-font d' , the wick-tube a' being secured to the upper end of said oil-font, and g is the wick. 3 represents a bracket in the lower portion of the oil-font; h , a band which extends around the 90 wick and is provided with spaced-apart pronged arms h' , pivotally connected thereto, said arms being adapted to lie against the outer surface of the wick and the prongs thereof to engage the same. This band h is 95 provided with an interiorly-threaded portion, through which the screw-rod 10 passes, the lower end of said rod 10 passing through an aperture in the bracket 3.

I provide a casing i of sheet metal connected 100

by screws 4 to the upper end of the oil-font, and upon a flat surface provided therefor and adjacent thereto the oil-font is provided with a guide-tube 5. The screw-rod 10 passes through the guide-tube 5 and through a sleeve 11 and through a rack-tube 9, the sleeve 11 being fixed to the screw-rod 10 and the rack-tube 9 rectangular in cross-section and passing through a corresponding opening in the case. Above said rack-tube, secured to the threaded end of the rod 10, is a head 12. Within the case *i* is a pinion 6, meshing with the rack-tube 9. Said pinion is upon a stem 7, the free end of which is provided with a knurled disk 8 outside the case. The rotation of the pinion 6 by the knurled disk 8 moves the rack-tube 9, sleeve 11, head 12, and the screw-rod 10 down and up with a vertical movement and with said movement lowering and raising the band *h*, pronged arms *h'*, and the wick *g*, the sleeve 11 forming a stop for the upward movement in the position Fig. 5 and the head 12, coming against the exterior of the casing *i*, a stop for the downward movement of the parts.

The head 12, screwed upon the upper end of the rod 10, is free from the rack-tube 9, there being a slight play, so that by turning the head 12 the screw-rod and sleeve 11 may be rotated, said rod turning in the interiorly-threaded hub portion of the band *h* to raise or lower the band, the pronged arms *h'*, and the wick *g* and adjust the height of the wick with reference to the position of the rack-tube 9, so as to bring the wick when fully elevated at the proper height for a smokeless flame, the wick when depressed by the movement of said parts going sufficiently low within the wick-tube *a'* to insure the flame going out.

I have shown and preferably employ a friction-spring 13 (see Fig. 5) in the form of a bent wire, the free ends of which grasp the stem 7; but this device being old in the art forms no part of my invention.

In the form of my invention shown in Figs. 7 and 8, *k* represents the font for the burning fluid; *c*, the central-draft tube; *g*, the wick; *l*, a band surrounding the wick and secured thereto by a device like the pronged arms *h'*, Figs. 4 and 5, or by any equivalent structure, and *m* is a bracket engaging the band *l*. The font *k* is provided with a vertically-placed tube *n*, extending from near the base of the font up within the same and above the font, and with an auxiliary tube *n'* in the upper end of the font concentric and surrounding the upper end of the tube *n*. In the annular space between the tubes *n* and *n'* there is a tube *o*, secured at its lower end to the bracket *m* and normally extending above the upper ends of the tubes *n* and *n'*. The upper end of the tube *o* is closed except for an opening providing for the threaded upper end of the screw rack-rod *r*, which passes through and substantially fills the tube *n*. A knob 14 is on the upper end of

this screw rack-rod *r* and a similar knob on the lower end. The rod *r* passes out of the lower end of the tube *n* and through a casing *i'*, similar to the casing *i*, (shown in Figs. 4 and 5,) but inverted in its position, said casing being secured to the lower portion of the font by screws 15. A stem 17 passes through this casing, and on one end thereof is a pinion 16, engaging the rack-teeth of the rod *r* and on the other and outer end a knurled disk 18, by the turning of which with said stem and pinion the screw rack-rod *r* is raised and lowered. *s* is a nut adjustable longitudinally upon the screw-rod *r*.

The position of the parts Figs. 7 and 8 represents the extreme upward movement in which the nut *s* comes against the lower end of the casing *i'* and in which position the wick is supposed to be at the proper height for a smokeless flame. With the movement of the parts and the descent of the rod *r* the wick is lowered, and the limit of the downward movement is determined by the inner upper end of the tube *o* coming against the fixed upper end of the tube *n*. As the wick burns and it becomes necessary to increase the height of the same the nut *s* is rotated on the rod *r* and lowered. This when the parts are returned to the position Figs. 7 and 8 permits the wick to be raised to the former height and to the required or proper height for producing a smokeless flame.

The several forms of my invention illustrated embrace a device capable of arresting the movement of the rack-and-pinion device, so as to regulate the opposite movements of the wick, and also a device having an adjustable feature for regulating the extent of the upward movement of the wick.

I claim as my invention—

1. In a wick-raiser the combination with a rack and pinion, of a device coacting therewith and adjustable so as to bring the wick to the desired or predetermined position according to the height of the flame required, the adjustable function being performed when the rack-and-pinion device are at an extreme of their movement.

2. In a wick-raiser, the combination with a rack and pinion, of a part passing through a part thereof and having a regulatable function, and associated means for limiting the upward and downward movement of the wick.

3. In a wick-raiser, the combination with a rack and pinion, of a vertically-movable screw-rod, a part connected thereto and movable therewith and adapted to engage the wick so that the wick is caused to rise and fall with the vertical movement of said screw-rod, and means associated therewith for limiting the extremes of this movement in opposite directions.

4. In a wick-raiser the combination with a rack and pinion, of a screw-rod passing vertically through the font, a guide therefor connected to the font, a case through which the screw-rod passes, the rack of the rack-and-

pinion structure being carried by said rod, and devices associated with said rod for limiting the extreme upward and downward movement of the parts and of the wick.

5. In a wick-raiser, the combination with the oil-font and a guide-tube carried thereby and extending within the font, of a casing, and means for securing the same to the font, a pinion within the casing, a stem and a knurled disk for turning the same, a rack engaged by said pinion, and a vertically-movable screw-rod associated therewith, devices connected to the screw-rod and engaging the wick for raising and lowering the same, and means associated with the screw-rod for limiting the extremes of the upward and downward movements of the wick.
6. In a wick-raiser, the combination with the oil-font and a guide-tube carried thereby and extending within the font, of a casing, and means for securing the same to the font, a

pinion within the casing, a stem and a knurled disk for turning the same, a screw-rod passing vertically within the font through said case and guide-tube, a rack-tube surrounding said screw-rod and engaged by the pinion, a sleeve secured to said screw-rod at one end of the rack-tube, and a head secured to the upper end of said screw-rod above said rack-tube, and by means of which head the screw-rod is rotated, a band having an interiorly-threaded hub portion through which said screw-rod passes, and devices connected to the band for engaging the wick; whereby with the rotation of the screw-rod the band and the wick connected thereto are raised and lowered.

Signed by me this 31st day of January, 1903.

CHAS. E. WIRTH.
